UNITED STATES PATENT OFFICE.

EDWIN C. HAWKINS, OF NOBLESVILLE, INDIANA.

PROCESS OF COATING PAPER CONTAINERS.

1,301,841.

Specification of Letters Patent. Patented Apr. 29, 1919.

Application filed July 8, 1918. Serial No. 243,686.

To all whom it may concern:

Be it known that I, EDWIN C. HAWKINS, a citizen of the United States, residing at Noblesville, in the county of Hamilton and State of Indiana, have invented new and useful Processes of Coating Paper Containers, of which the following is a specification.

It is the object of my invention to water-proof paper containers, especially of the mailing tube type where the body of the container is formed of a plurality of superposed layers of suitable paper wound helically with broken joints, and where the ends of the tube are provided with separate end members, for closing such ends.

Many articles must not only be protected while in storage or transit, but must be kept free from moisture, because they would be spoiled if permitted to become wet or even damp. Containers of the mailing tube type have not heretofore been suitable for such articles, for attempts effectively to water-proof such containers, against submergence for instance, had not been successful. This was largely because of the joints in these containers, both between the adjacent turns of the helical winding and between the body of the container and its end pieces, which joints gave water ready access to the edges of the paper layer so that it could soak edge-wise through them. By reason of the structure of the paper used for such tubes, such as strawboard and test board, this is much easier than soaking transversely therethrough.

By my present invention, I not only make the paper container impervious to water transversely, but also water-proof the joints both in the body of the container and between such body and the end pieces, thus preventing access of water to the edges of the paper layers. I do this by applying a solution of rubber in some volatile solvent over the surface of the container, and most particularly over the joints, permitting the solvent to evaporate to leave a thin film of rubber over the surface to which the solution is applied, then preferably applying a second coat of the same solution and allowing its solvent to evaporate, and then vulcanizing the rubber film in position on the surface of the container and over the joints thereof. The article, the water-proofed paper container, which is produced by this process, is

claimed in my co-pending application Ser. No. 243,685, of even filing date herewith.

The accompanying drawing illustrates my invention. Figure 1 is a perspective view of a waterproof paper container which has been 60 water-proofed in accordance with my invention; and Fig. 2 is a partial longitudinal section through such a paper container, of somewhat different form and on a somewhat larger scale, and with the thickness of 65 the walls and the rubber coating magnified, to show more clearly how the rubber coating overlaps the joints.

The body of the container comprises a plurality of layers 10, of suitable paper such as 70 strawboard or test-board, wound helically upon one another to form a tube, in the usual manner of mailing tubes. The joints 11 of the successive layers break with one another, so that beneath such joints of each layer 75 there is a jointless surface of the adjacent layer. The end members of the tube fit over or within the tube, as desired, in the latter case some of the outer layers of the tube near the end preferably being folded in 80 upon themselves so as to leave no raw edges exposed. The end pieces may be of material similar to that of the tube, as is the permanently closing end disk 12 of Fig. 2; or may be of metal, as are the end pieces 13 of Fig. 85 2 and the end bands 14 and 15 of Fig. 1. If of metal, they may be parts of closing end caps, as in the band 14; or they may or may not be provided with internal or external screw threads, as are the end 90 piece 13 and the end band 15, for receiving a detachable closing piece, such as the end cap 16 of Fig. 1. In the particular containers shown, a paper closing disk is shown inserted in one end of the container body 95 of Fig. 2, and metal end caps or bands are shown encircling the other end of the container in that figure and both ends of the container in Fig. 1; but these are merely illustrative arrangements, to show both an 100 inserted and an encircling end piece and both a paper and a metal end piece, and neither arrangement is essential. The paper container itself is old, and may take various forms; *per se*, it is not my invention. 105

In order to water-proof the container, I first apply to one or both surfaces—as illustrated, to the outside surface—a solution of rubber in some volatile solvent, such as benzol, gasoline, carbon tetra-chlorid, or carbon 110

bisulfid; particularly I spread this solution over the helical joints 11 between the adjacent edges of successive turns of the paper layer forming the surface being coated and over the joints 17 between the body of the container and the end pieces 12, 13, 14, or 15. When the end pieces are paper, such as the disk 12, I apply the solution over the corresponding surface thereof as well as over 10 the entire surface of the tube; and when they are metal, such as the end piece 13 and the end bands 14 and 15, I apply the solution over the joints 17 and part way up onto the metal. Preferably I apply this solution 15 with a brush, brushing in both directions; and particularly I brush in both directions over the helical joints 11 so as to cover both raw edges at such joints. I find the best results are obtained if the brushing over the 20 joints 11 is done obliquely to such joints, as by brushing in planes perpendicular to the tube axis. After the solution has been applied, the solvent is permitted to evaporate, preferably in a current of hot air to expedite the evaporation. This leaves a first thin 25 film of rubber on the surface to which the solution was applied and spanning the joints 11 and 17. This first coat acts as a filler, to some extent, to fill the pores of the paper. 30 After the solvent of the first coat has evaporated, a second coat of the rubber solution is applied over the first coat, care being taken as before to cover the joints 11 and 17; and then the solvent of this second coat is allowed to evaporate. This leaves a second 35 rubber film superposed upon and coalescing with the first, to form a rubber coating 18 covering and spanning the joints 11 and 17. Then this rubber coating 18, if obtained 40 from a non-vulcanizing solvent such as gasoline, benzol, or carbon tetrachlorid, is exposed to a suitable vulcanizer, such as sulfur chlorid. The vulcanizer may be applied with a brush as a liquid, or the rubber 45 coating may be exposed to the fumes of the vulcanizer. The vulcanizing process is continued until the desired quality of rubber in the coating is obtained. However, if the rubber solvent used is itself a vulcanizer, 50 vulcanization is produced thereby, and no other vulcanizer need be applied.

The rubber solution and the vulcanizer may be applied by hand or by machinery, one machine for applying them to open- 55 ended tubular containers being shown in the co-pending application of Charles B. Macy, Ser. No. 243,629, of even filing date herewith.

This produces a container which is sub- 60 stantially water-proof under rigid tests. It may be submerged in water under consider- able pressure for considerable lengths of

time, without any seepage of moisture through it. It may therefore be used for storing and transporting materials which must be kept dry but which are in danger 65 of exposure to moisture in storage or transit; such as gun shells, shell timers, medical and surgical and hospital supplies, and also many other articles useful in both war and peace. The container may also be used as 70 the permanent casing of many articles, such for instance as hand grenades, the contents of which must be kept dry. By applying the rubber solution to the inside surface, instead of to the outside surface, the container is 75 protected from internal moisture, so that it may be used as a holder for such liquids as do not re-act upon or dissolve rubber.

I claim as my invention:

1. The process of water - proofing a paper 80 container having joints in its surface, which consists in applying over the joints in the surface of such container a solution of rubber in a volatile solvent, permitting the solvent to evaporate to leave a film of rubber 85 spanning such joints, and vulcanizing such film of rubber.

2. The process of water - proofing a paper container having joints in its surface, which consists in applying to the surface of such 90 container and over the joints in such surface a solution of rubber in a volatile solvent, permitting the solvent to evaporate to leave a film of rubber covering such surface and spanning such joints, and vulcanizing such 95 film of rubber.

3. The process of water - proofing a paper container having joints in its surface, which consists in applying over the joints in the surface of such container by brushing in 100 both directions across such joints in lines oblique to such joints a solution of rubber in a volatile solvent so as to cover the raw edges at such joints, permitting the solvent to evaporate to leave a film of rubber spanning such joints, and vulcanizing such 105 film of rubber.

4. The process of water - proofing a paper container having joints in its surface, which consists in applying over the joints in the surface of such container by brushing in both directions across such joints a solution of rubber in a volatile solvent so as to cover the raw edges at such joints, permitting the solvent to evaporate to leave a film of rubber 115 spanning such joints, and vulcanizing such film of rubber.

In witness whereof, I have hereunto set my hand at Indianapolis, Indiana, this 21st day of June A. D. one thousand nine hundred and eighteen.

EDWIN C. HAWKINS.
